CLAIM

The ornamental design of a shower brush head adapter, as shown and described.

DESCRIPTION

FIG. 1 is a perspective view of the shower brush head adapter;

FIG. 2 is a top view thereof;

FIG. 3 is a bottom view thereof;

FIG. 4 is a right side view thereof;

FIG. 5 is a left side view thereof;

FIG. 6 is a rear end view thereof;

FIG. 7 is a front end view thereof;

FIG. 8 is a perspective view thereof with a loofah supported thereon; and,

FIG. 9 is a perspective view thereof with a sponge supported thereon.

The handle shown in broken lines in all figures, and the loofah and sponge shown in broken lines in FIGS. 8 and 9 illustrate environmental structure and form no part of the claimed design.

1 Claim, 5 Drawing Sheets
